BLADE HANDLING DEVICE

Joseph Muros, Cambridge, Mass., assignor to
Gillette Safety Razor Company, Boston, Mass.,
a corporation of Delaware

Application May 24, 1945, Serial No. 595,608

18 Claims. (Cl. 30—40)

1

This invention consists in an improved blade-handling device having several related and simultaneous functions: In the first place, it serves as a dispensing blade package for a single safety razor blade, a package in which the blade may be safely enclosed by the manufacturer and maintained by the dealer and user without danger to its keen edge or edges. In the second place, it serves as an insertor by which the fresh sharp blade may be inserted in a safety razor without danger of its being touched by the user, the blade being deposited accurately in shaving position. In the third place, the device serves as a receiver for a used blade, engaging it in the razor and withdrawing it in fully guarded condition. And finally, it serves as an expendable guard which may be thrown away with the used blade and so provides a satisfactory solution for the problem of safe disposition of used blades. The device may also be used as a guard for the assembled razor, or rather, as a guard for a blade located in a safety razor.

In one aspect, the blade-handling device of my invention comprises a thin, elongated body having on one face a fresh blade held in place by means which permit the blade to be detached and removed from the device, preferably in an endwise direction, and on the other face, means, such for example as spaced projections, for gripping the opposite edges of a used blade. It is believed that the provision of blade-engaging means on opposite sides of a thin, stiff blade-handling device is broadly novel and the related and supplementary functions of delivering fresh blades and collecting used blades have not been heretofore combined in a single blade-handling device of this general type.

An important feature of the invention consists in the manner of mounting the fresh blade upon one face of the blade-handling device. As herein shown, co-operating sheets of cardboard or other somewhat resilient members are secured together in advance of or beyond the edges of the blade interposed between them. These members may fit against the beveled faces of the blade edge or the heel of the bevel while leaving its extreme cutting edge entirely free and clear of contact. This results from the fact that the blade-engaging sheets are directed to a line of intersection substantially outside and beyond the line of the cutting edge and converge at an angle more acute than that of the blade bevel. The fresh blade may be thus temporarily and detachably held in its position and is at the same time free to be removed from the blade-holding device by movement relatively to the device in an endwise direction.

It is important to locate the fresh blade on one side of the blade-holding device in predetermined relation to guiding means provided on the other

2

side of the device for registering it with one of the blade-clamping members of the safety razor with which it is to be employed.

Preferably and as herein shown, the upper face of the blade-handling device is provided with means, such as parallel ways, which have the double function of guiding the device as a whole into operative relation with the razor head by engaging the edges of the razor cap and providing means for engaging the opposite edges of a used blade already located beneath the cap.

These and other features of the invention will be best understood and appreciated from the following description of two preferred embodiments thereof, selected for purposes of illustration and shown in the accompanying drawings, in which:

Fig. 1 is a view in perspective of the complete device containing a single safety razor blade ready for distribution, the device being shown enlarged to substantially twice its natural size and in inverted position;

Fig. 2 is a corresponding view of the device in the position in which it is used;

Fig. 3 is a view in cross-section on the line 3—3 of Fig. 1;

Fig. 4 is a fragmentary view in cross-section on a still greater scale;

Fig. 5 is a view in perspective illustrating the step of moving the blade-handling device into blade transferring relation to the head of a safety razor;

Fig. 6 is a corresponding view of the safety razor and blade-handling device as seen from beneath;

Fig. 7 is a view in cross-section on the line 7—7 of Fig. 8;

Fig. 8 is a view in longitudinal section on the line 8—8 of Fig. 6 but shows the blade-handling device fully inserted;

Fig. 9 is a view in perspective showing a blade in position upon the blade-supporting member or guard of the razor;

Fig. 10 is a view in perspective of a second embodiment of the invention in inverted position;

Fig. 11 is a view in cross-section on the line 11—11 of Fig. 10;

Fig. 12 is a view corresponding to Fig. 10, showing the device in normal position; and

Fig. 13 is a view in cross-section on the line 13—13 of Fig. 12.

The blade-handling device shown in Figs. 1 and 2 may be constructed of any suitable material such as cardboard, wood or a molded plastic material stiff enough to be pushed inwardly between the cap and guard of a safety razor. It comprises a solid elongated body 10 approximately rectangular in shape although preferably rounded at its rear end and having a short wide tongue centrally disposed in its

square front end. In one face of the body 10 is provided a rectangular recess 11, shown uppermost in Fig. 2, which opens through the front end of the device above its tongue and is defined by parallel ribs or flanges 12 and 13 forming undercut ways and an inner transverse end wall 14. This gives the device relatively thick and stiff edge portions connected by a thinner intermediate web. The device herein shown is designed to handle double-edged slotted blades of a well-known commercial type, closed at both ends and having a longitudinal median slot 17 with local enlargements, as best shown in Fig. 9. The recess 11 in the face of the device is of proper dimensions to receive such a blade while the flanges 12 and 13 grip it frictionally by edge engagement, thus holding it with its slot in unobstructed position on the face of the body 10 and with both sharp edges completely guarded.

For convenience and to prevent confusion, that face of the blade-handling device upon which the new blade is mounted may be marked "New Blade" and the flanged face of the device, which is eventually to receive a used blade, may be marked "Used Blade." In Figs. 2, 5, 6 and 7, the "used blade" face of the device is shown uppermost and will be herein termed the upper face.

The lower face of the web is provided centrally with a shallow longitudinal channel 15 which opens through the tongue in the front end edge of the device. A slotted double-edged blade 16 is temporarily secured to this face of the body 10, being symmetrically disposed below the web and with the channel 15 providing a clearance space above the blade slot 17 for the blade-locating projections of the razor head. As herein shown, the blade 16 is secured in position by a flexible cover sheet 18 of paper, fibre or the like, and this is cemented about its margins to the lower face of the body 10 and overlaps both edge portions of the blade 16. The sheet 18 is provided with a central slot 19 of substantially the same width as the channel 15 so that the outline of the blade slot 17, with its intermediate enlargements, is fully exposed.

It will be understood that the blade manufacturer may place the fresh sharp blade 16 accurately in position upon the lower face of the body 10 and then secure it in that location by cementing the margin of the cover-sheet 18 in place. The blade is thus located symmetrically and accurately with respect to the flanges 12 and 13 and this is important, since the proper positioning of the device as a whole for blade delivery is determined by the undercut ways of these flanges. The cover sheet 18 may be cemented to the lower face of the body 10 nearly up to the sharp edges of the blade 16, but the sheet can never be brought actually into contact with the cutting edge of the blade, as clearly shown in Fig. 4, because the bevel of the extreme blade edge is less acute than the angle between the upper and lower blade-engaging elements as they converge into contact along a line outside the cutting edge. They provide in effect parallel ways upon the lower face of the body 10 for guiding the fresh blade in endwise movement, but without touching its cutting edges.

In Figs. 5-9 is shown one type of safety razor adapted to be served by the blade-handling device of my invention. This razor comprises a handle 20 carrying a blade-supporting or guard member 21 having an upper convex blade-supporting face. A cap member 22 is detachably connected to the guard 21 by an arm 23 which extends

around and beneath one end of the guard and is forked to engage the upper end of the handle 20. A forked spring 24 fast to the under face of the cap tends normally to separate the cap and guard to the extent permitted by the arm 23 and thus to provide a blade passage between them. The cap 22 is provided with a central threaded socket 25 and with this co-operates a threaded spindle 26 telescopically received within the handle. The guard member 21 is centrally perforated to permit passage of the threaded spindle 26 and is provided with a longitudinal upstanding rib 27 symmetrically disposed in one end of the blade-seat and supplemented by a shallow diamond-shaped stud 28 which is of the proper shape to fill one of the enlargements of the slot 17 in the blade.

The blade-engaging face of the razor cap 22 is somewhat concave in cross-section and its longitudinal edges fit in the undercut ways formed by the ribs 12 and 13 of the blade handling device, as well shown in Fig. 7. The blade is positioned on the guard 21, as shown in Fig. 9, being located centrally by the rib 27 and slightly overhanging the guard 21 at both ends of the razor. When it is desired to replace a used blade in the razor, the end tongue of the blade-handling device is brought into contact with the under face of the projecting end of the used blade 16', lifting it slightly from the blade seat but always enough to free it from the shallow stud 28 and to permit the advancing end of the fresh blade 16 to be inserted in the razor head beneath the used blade 16' and above the blade-seat. In this operation the undercut guideways of the ribs 12 and 13 in the upper face of the blade-handling device are registered with the longitudinal edges of the cap 22, and the device is accurately guided by the edges of the cap so that the fresh blade 16 passes beneath the used blade 16' and becomes fully and accurately seated upon the blade-seat of the razor with its slot 17 fitting the rib 27 and an intermediate enlargement of the slot fitting the shallow stud 28. Meanwhile the used blade has passed into the recess 11 above the web in the body of the blade-handling device and in this movement its opposite edges are engaged by the ways formed by the ribs 12 and 13 as well shown in Fig. 7. When the blade-engaging device has been advanced through half of its normal path as shown in Fig. 5 the fresh blade has been advanced over the rib 27 and halfway along the blade seat of the razor, while the used blade 16' has been advanced half-way into the recess 11. In Fig. 8 the blade-handling device is shown as advanced to its final position, the used blade 16' having engaged the inner end wall 14 of the recess 11 and the fresh blade 16 having received the rib 27 and being fully seated and positively held in shaving position on the blade-seat.

If desired, and as herein shown, the front edge of the cover sheet 18 may be extended downwardly in the form of tongues 29 over the shoulders of the outer end of the blade 16. These tongues positively retain the blade in place but may be easily broken when the device is retracted from the razor head, leaving the blade positioned therein for shaving.

Now, when the device is retracted, moving toward the right in Fig. 8, the used blade 16' remains gripped between the ribs 12 and 13 and is withdrawn with the device, while the fresh blade 16, positively held by the stud 28, remains in proper position on the blade-seat. The user has now only to screw down the spindle 26 to prepare

the razor for shaving, and may throw away the blade-handling device containing only the used blade in fully guarded condition.

A second embodiment of the invention is illustrated in Figs. 10-13 in which the blade-handling device or insertor is shown as having an elongated body portion 30 rounded at its rear end and notched in its forward end to provide a projecting tongue 31 designed to underlie the elongated unsharpened end portion of a new blade 16. The body 30 is provided in its longitudinal edges with opposed inturned flanges 32 and 33 shaped to engage the bevel of the new blade 16 but not its cutting edge as clearly indicated in Fig. 11. The body 30 is provided with a longitudinal slot 34, herein shown, but not necessarily, somewhat shorter than the length of the blade slot 17, and in general providing clearance for any projection in the razor designed to pass through the slot 17 or the enlargements therein.

The flanges extend for about one-half the length of the blade edge and a tongue 35 is struck out of the material of the rounded end portion of the body 30 and turned in so as to overlap and hold the solid inner end portion of the blade. The new blade is thus detachably retained in the device by oppositely disposed guideways which engage it frictionally while permitting it to be removed by endwise movement, and by the end tongue 35 which positively prevents its displacement rearwardly in the device.

The device is shown in Fig. 12 as being provided with a second set of flanges 36 and 37 which are inturned over the upper face of the device and occupy that portion of the longitudinal edges thereof to the rear of the portion occupied by the inturned flanges 32-33 on the lower face of the device. The flanges 36 and 37 are disposed somewhat closer together than the flanges 32 and 33, being designed to retain a used blade 16' by gripping its sharpened edges. The forward ends of the flanges 36 and 37 are flared somewhat upwardly and outwardly to facilitate entering the device in the head of a safety razor. The body 30 of the device comprises a wall or shield beneath which a new fresh blade is supported and above which a used blade is engaged for removal from the safety razor. This embodiment of the invention may advantageously be constructed of sheet metal, Celluloid or other material stiff enough to be pushed inwardly between the cap and guard of the safety razor.

In use, the device is brought up to the head of a safety razor and the tongue 31 inserted beneath the projecting end of the used blade, lifting it upwardly from the blade-seat sufficiently to permit the entrance of the end of the fresh blade beneath it. The device or "insertor" as it may be called, is advanced longitudinally until the fresh blade has fully settled itself in shaving position where it is positively held against retraction by the action of the shallow stud 28 in filling one of the intermediate enlargements of the slot 17. In this movement, the end of the used blade is passed above the body 30 of the insertor and its edges enter between the flanges 36 and 37. When the insertor has been moved to the inner limit of its bevel, the used blade 16' is fully seated upon the upper face of the body 30, being retained thereon by the flanges 36 and 37. Accordingly when the device is moved outwardly, the used blade 16' remains in this position and is withdrawn while the fresh blade remains properly positioned for shaving in the head of the safety razor.

The difference between the gripping action of the flanges 32 and 33 on the beveled portion of the blade, but not its cutting edges, and the gripping action of the flanges 36 and 37, which is such as to dull the edges of the used blade, is well shown in Figs. 11 and 13.

Having thus disclosed my invention and described in detail illustrative embodiments thereof, I claim as new and desire to secure by Letters Patent:

1. The combination of a safety razor having separable cap and guard with a blade-handling device comprising a thin, stiff body having on one face a sharp unused blade and means for detachably retaining the blade while leaving it free to be withdrawn in an endwise direction, and on its other face parallel ways for guiding the device on the cap of a safety razor, whereby the said blade may be located symmetrically beneath the cap.
2. The combination of a safety razor having separable cap and guard with a blade-handling device comprising an elongated body having on its lower face a sharp unused blade held for removal only in an endwise direction, and on its upper face undercut ways for guiding the device as a whole into registration with the cap of a safety razor and for engaging the opposite edges of a used blade in the safety razor.
3. The combination of a safety razor having separable cap and guard with a blade-dispensing device for a single safety razor blade, comprising an elongated body having thick edge portions connected by a thin intermediate web, parallel ways in said edge portions for guiding the device as a whole into operative relation with a safety razor head, and a fresh blade detachably mounted in partially exposed position on one face of the said web.
4. The combination of a safety razor having separable cap and guard with a blade-handling device for safety razor blades, comprising a body having thick longitudinal edge portions and a thin intermediate web, guideways in said edge portions constructed and arranged to make sliding contact with the edge portions of a safety razor and to locate said web above blade-engaging projections of the razor, and a fresh blade detachably in partially exposed position on the lower face of said web.
5. The combination of a safety razor having separable cap and guard with a blade insertor having an elongated body with parallel guideways on one face thereof and an apertured blade symmetrically disposed on its other face; the safety razor cap having longitudinal edges fitting the guideways of the insertor, and a guard member having projections so located as to engage the blade thus presented by the insertor.
6. The combination of a safety razor having separable cap and guard with a blade insertor having an elongated body with parallel flanges on one face thereof and a slotted blade symmetrically disposed on its other face, one end of the blade being covered and the other partially free; the safety razor cap having longitudinal edges fitting between said flanges, and a guard member maintained in parallel relation to the cap and provided with a rib for engaging the blade slot when the flanges of the insertor are engaged with the edges of the razor cap.
7. The combination of a safety razor having separable blade clamping members with a blade-handling device comprising a thin elongated body shaped to be inserted between the cap and guard of a safety razor, means on one face of said body

constructed and arranged to receive and engage the opposite edges of a blade presented endwise to said body and for retaining the blade thereon, a fresh blade held in exposed position on the other face of said body, and means constructed and arranged to retain said fresh blade in position thereon and to release it by endwise movement of said body in a direction opposite to that in which the used blade is received.

8. The combination of a safety razor having separable cap and guard with a blade-handling device according to claim 7, including means on said body for co-operation with the head of a safety razor constructed and arranged for guiding the device in its movement on said head.

9. The combination of a safety razor having separable cap and guard with a device for inserting a new blade into a safety razor and for withdrawing a used blade therefrom, comprising a thin elongated body, means on one face of said body for receiving and retaining the used blade thereon with its cutting edge within the perimeter of said body, a fresh blade on the other face of said body, and means for detachably retaining said fresh blade in exposed position thereon.

10. The combination of a safety razor having separable cap and guard with a device according to claim 9, including means on said body for guiding the device in its movement on the razor.

11. A blade dispensing and receiving device comprising an elongated body having a thin intermediate web bordered by thick longitudinal ribs having undercut opposed faces forming ways adjacent to one face of the web, the web having therein a shallow medial longitudinal channel in its other face, and a slotted closed-end blade detachably mounted in direct contact with the said other face of the web with the channel providing clearance space beneath the slot of the blade.

12. A device for the introduction of a fresh sharp razor blade of the double-edge closed-end type into a razor head and for the removal of a similar used blade from that razor head, comprising a thin elongated body having on one face longitudinal parallel flanges overlying the marginal edges of said body and being spaced to grip a used blade along its opposite edges and to guard said edges, a single fresh closed-end blade located in position directly on the other face of the thin body, and means for temporarily holding the fresh blade in said position, whereby a fresh and a used blade may be located between the cap and guard of a safety razor while the said blades have only the thin body of the device interposed between them.

13. A blade dispensing and receiving device comprising a thin elongated body having on one face projections with oppositely arranged walls spaced apart and cooperating for engaging a double edged used blade along both its sharp edges and to guard the said edges, a single fresh closed-end blade located in direct contact with the other face of said thin body and being so disposed that used and fresh blades may be located in close proximity to each other between the cap and guard of a safety razor with only the thin body of the device interposed between them, and means for releasably retaining said fresh blade in position upon the face of the thin body.

14. A blade dispensing and receiving device comprising a thin elongated body having on one face upstanding parallel ways stiffening the body and having opposed walls spaced apart to engage a used double-edged blade by its opposite sharp edges and completely to guard said edges, the

other face of said body being substantially smooth, a single fresh closed-end blade located in direct face-to-face contact with said other face and being so disposed thereon that a used and a fresh blade may be located in close proximity to each other between the cap and the guard of a safety razor with only the thin body of the device interposed between them, and means for releasably retaining said fresh blade in position without contacting its sharp edges.

15. An expendable blade dispensing and receiving package having a thin elongated body portion, a fresh double-edged closed-end blade detachably mounted directly on one face of said thin body portion and in contact therewith, and longitudinal ribbed projections on the other face of said thin body portion having walls spaced apart and shaped to engage the opposite sharp edges of a similar but used double-edged closed-end blade and completely to guard both said edges, whereby a used and a fresh blade may be located in close superposed proximity to each other between the blade-clamping members of a safety razor and with only the thin body of the device interposed between them.

16. A device for the introduction of a fresh sharp razor blade of the double-edge closed-end type into a razor head and for the removal of a similar used blade from that razor head, comprising a substantially rectangular elongated body of thin sheet material of dimensions exceeding the length and breadth of said blades, said body having on its underside means for temporarily holding said fresh blade substantially wholly within the rectangular outline of said body and in contact with said underside, and a pair of opposed flanges extending alongside the longitudinal margins of said body and overlapping the upper surface thereof, said flanges being spaced progressively to embrace and guard the cutting edge regions of said used blade as the device is advanced into said razor head, whereby said fresh and said used blades may both be located in the razor head in close proximity to each other and separated only by the intervening thin body of the device.

17. A device for introducing a fresh sharp razor blade of the double-edge closed-end type into a razor head and for removing a similar used blade from that razor head, comprising a substantially rectangular elongated body of thin sheet metal of dimensions exceeding the length and breadth of said blades, said body having a pilot projection in its front edge and on its underside means for temporarily holding said fresh blade substantially wholly within the rectangular outline of said body and in contact with said underside, and a pair of opposed flanges inturned over the longitudinal margins of said body and overlapping the upper surface thereof, said flanges being adapted progressively to embrace and guard the cutting edge regions of said used blade as the device is advanced into said razor head and the pilot passes beneath the used blade, whereby said fresh and said used blades may both be located by the device in said razor head in close proximity to each other, being separated only by the thin sheet metal body of the intervening blade-handling device.

18. The combination of a safety razor having separable cap and guard with a blade-handling device comprising a thin elongated body shaped to be inserted between the cap and guard of a safety razor, means on one face of said body for receiving and retaining a used blade thereon, said

means cooperating with the head of the safety razor and being constructed and arranged for guiding the device in its movement on said head, a fresh blade on the other face of said body and means for detachably retaining said fresh blade in exposed position thereon.
